UNITED STATES PATENT OFFICE.

WILLIAM DIEBEL, OF PHILADELPHIA, PENNSYLVANIA.

TUBE-COILING APPARATUS.

1,124,874.

Specification of Letters Patent.

Patented Jan. 12, 1915.

Application filed January 17, 1914. Serial No. 812,673.

To all whom it may concern:

Be it known that I, WILLIAM DIEBEL, a citizen of the United States, residing at Philadelphia, in the county of Philadelphia and State of Pennsylvania, have invented 5 certain new and useful Improvements in Tube-Coiling Apparatus, of which the following is a specification.

My invention relates to improvements in 10 tube coiling apparatus, the object of the invention being to provide an improved apparatus which will rapidly coil tubing of very thin metal without the necessity of filling the tube with sand, rosin, lead, or other material to prevent collapsing.

While, of course, my invention is not limited to any particular thickness of metal, my apparatus enables me to coil tubing which would with ordinary apparatus be 20 come flattened out like a ribbon if any attempt were made to coil the same, and as this very thin metal tubing greatly facilitates the interchange of temperatures, it can be used with great success in water heaters 25 for many uses.

With these and other objects in view, the invention consists in certain novel features of construction and combinations and arrangements of parts as will be more fully 30 hereinafter described and pointed out in the claims.

In the accompanying drawings: Figure 1 is a view in elevation illustrating one form of my improvements. Fig. 2 is a fragmentary view in longitudinal section. Fig. 3 is an end elevation of the tube guiding head and its handle. Figs. 4, 5, and 6 are views similar to Figs. 1, 2, and 3, illustrating a modification, and Fig. 7 is a view in cross section on the line 7—7 of Fig. 6.

1 represents a mandrel provided with a spiral groove 2, and at one end made angular as shown at 3 for attachment to the chuck of any ordinary lathe or other apparatus for turning the mandrel.

4 represents a metal tube which is adapted to be coiled around the mandrel 1 in the groove 2, and it will be noted particularly by reference to Fig. 2, that the groove is of 50 a width appreciably greater than the diameter of the tube, but of a depth approximately the same as the diameter of the groove, so that when the tube is coiled within the groove, it can be readily removed 55 and not bind in the groove as would be the

case if the diameter of the tube and groove were of substantially the same dimensions.

With my improved apparatus, it is neither necessary nor desirable that the tube be heated, but while cold is guided into place around the mandrel by means of an improved head 5 which is of general cylindrical form and of an internal diameter slightly larger than the diameter of the mandrel. This head 5 comprises a sleeve 5^a 60 provided at one end with a ring 6, and the meeting surfaces of the ring 6 and sleeve 5^a are at an angle to the longitudinal axis of the head and the mandrel, so that a plate 7 65 located between the ring and the sleeve is located at the same angle as the pitch of the groove 2 of the mandrel, and in bending the tube around the groove, this plate 7 acts as one wall of the groove.

The plate 7 is secured by screws 8 to the 70 head, and has an opening 9 appreciably smaller than the internal diameter of the head, so that the plate projects into the groove a sufficient distance to act as a wall of the groove in bending the tube as clearly 75 shown in Fig. 2.

A handle 10 is secured to the head, and a recess 11 is provided in the ring 6 to afford an entrance for the tube 4. The inner corner of one wall of this recess is rounded as 80 shown at 12 to prevent cutting or sharply 85 bending the tube.

The mandrel 1 is provided with an opening 13 adjacent its outer end in the groove 2, and in operation the end of tube 4, after 90 being projected through the entrance 11 in the ring 6, is projected into this opening 13 so that the revolution of the mandrel causes the tube to be bent around the mandrel and follow in the groove.

The handle 10 is held while the mandrel is revolved; and the tube 4 feeds through the entrance 11 and around the groove 2. This causes the head 5 to move longitudinally of the mandrel, and as above stated, 100 the plate 1 is positioned in the groove and acts as one wall of the groove while the tube is bent therein, so that each convolution of the tube is allowed a movement in the groove, and there is a loose connection 105 between the tube and the mandrel which permits the ready removal of the coiled tube after the operation is completed.

In the modification illustrated in Figs. 4, 5, 6, and 7, I employ a smooth mandrel 110

14 having an opening or recess 15 at one end to receive one end of the tube 4. With this smooth mandrel, I employ an internally and spirally grooved head 16 which 5 is made up of a plurality of rings secured together by screws 17.

The tube 4 enters the head at the point 18, and is guided around inside the head by the spiral groove 19, so that the revolution 10 of the mandrel winds the tube around the same as it is guided thereupon in a spiral coil by means of the internally spiral grooved head.

The groove 19 in the head is of a depth 15 sufficient to prevent a collapsing or mashing of the tube, and as in the other form of my invention above described, the head feeds longitudinally along the mandrel as the tube is spirally wound thereon. It is 20 therefore necessary to provide a handle 20 to hold the head, and this handle is grasped and held against rotary movement during the coiling operation.

It will be noted particularly by reference 25 to Figs. 1, 4, and 5, that the tube 4 is fed into the head and moves longitudinally of the handle. This permits the tube to be readily guided to the head, and in fact, the hand may readily grip the tube and the 30 handle as shown clearly in Fig. 1.

After the tube is completely coiled, the end which is located in the opening in the mandrel can be cut off and the tube readily removed from the mandrel.

35 Various other slight changes might be made in the general form and arrangement of parts described without departing from my invention, and hence I do not limit myself to the precise details set forth, but con-

sider myself at liberty to make such changes and alterations as fairly fall within the 40 spirit and scope of the appended claims.

Having thus described my invention, what I claim as new and desire to secure by Letters Patent is:

45 1. A tube coiling apparatus comprising a spirally grooved mandrel having means at one end for connection with the tube, a head fitting the mandrel and adapted to guide a tube into the groove, said groove 50 of a greater width and of approximately the same depth as the diameter of the tube to be coiled therein, and a plate carried by the head and movable in the groove, said plate constituting a movable wall of the 55 groove in which the convolution of the coil is being bent, substantially as described.

60 2. In a tube coiling apparatus, the combination with a spirally grooved mandrel, a head having a cylindrical bore fitting the mandrel, said head having an opening 65 through which a tube is adapted to pass and be guided by the head into the groove on the mandrel, said groove in the mandrel of a dimension to accommodate the entire 70 diameter of the tube and having an opening in one end into which one end of the tube is adapted to be projected to hold the tube against turning movement on the mandrel, substantially as described.

75 In testimony whereof I have signed my name to this specification in the presence of two subscribing witnesses.

WILLIAM DIEBEL.
